D. T. RANDALL.

HYDROCARBON MOTOR.

APPLICATION FILED APR. 11, 1917.

Patented Apr. 1, 1919.

INVENTOR:

DWIGHT T. RANDALL,

Dwight T. Randall
BY
ATTORNEY.

UNITED STATES PATENT OFFICE.

DWIGHT T. RANDALL, OF DETROIT, MICHIGAN, ASSIGNOR TO GENERAL MOTORS COMPANY, OF DETROIT, MICHIGAN, A CORPORATION OF NEW JERSEY.

HYDROCARBON-MOTOR.

1298,784.

Specification of Letters Patent. Patented Apr. 1, 1919.

Application filed April 11, 1917. Serial No. 161,228.

To all whom it may concern:

Be it known that I, DWIGHT T. RANDALL, a citizen of the United States, and resident of Detroit, Wayne county, State of Michigan, have invented certain new and useful Improvements in Hydrocarbon-Motors, of which the following is a specification.

This invention relates to hydrocarbon motors, and particularly to improvements in cooling systems especially adapted for use therewith.

One of the objects of this invention is to provide an internal combustion engine with a cooling system having adequate means for condensing and conserving any vapors which are formed by the cooling liquid.

The motor vehicle power plant, which is generally used, is provided with no adequate means for preventing loss of the motor cooling fluid either when the level rises above a predetermined point or when the temperature becomes so high that the liquid is vaporized. With such installations, when the motor is operating under high temperature conditions, the operator is subjected to the burden and annoyance of frequent replenishment of the cooling liquid. Such a condition results in considerable expense when costly anti-freeze solutions are used.

To overcome these and other objections, I have provided adequate means for preventing the loss of any of the cooling fluid from the system, either in a vapor or liquid state.

In general, my invention comprises a condenser connected with a circulating system at a point above the normal level of the liquid within the cooling system, and so located that it will always be subject to an adequate cooling action. In my preferred embodiment, the condenser is arranged in line with the radiator and a fan so that air will be directed over the condenser before passing through said radiator.

Another object is to provide an improved condenser for an internal combustion engine cooling system.

These and various other objects will appear from the following description taken in connection with the drawing which forms a part of this specification, and in which is illustrated a side elevation with portions broken away, of a motor vehicle power plant, embodying a preferred form of my invention.

Referring to the drawing, 10 represents

the usual crank case on which may be mounted in suitable "V" relation, a plurality of cylinder blocks, one of which is illustrated at 11, secured to the crank case by bolts 12. A radiator 13, and a fan 14, suitable driven from the engine, are arranged adjacent the front end of the motor and co-operate as will appear more fully hereinafter, to temper the liquid in the cooling system.

The cylinder block 11 is provided with the usual jacket 15, having an intake port 16, and an outlet port 17, suitable connections in the form of an intake conduit 18, a pump mechanism 19 of the well-known centrifugal type and a conduit 20, between the pump and the outlet port formed in the lower part of the radiator. Another flexible conduit 21 between the outlet port 17, and the radiator inlet port 18', a by-pass 19' connecting the conduits 20 and 21, and any well known valve, which may be located in a chamber 22 for controlling the circulation of the cooling medium, complete a double path circulating system between the radiator 13 and the cooling jacket 15 of the cylinder block 11.

The radiator 13 comprises an upper tank 23, a lower tank 24, and arranged intermediate thereof, are a set of radiating tubes 25 and a set of condensing tubes 26. The upper tank 23 is provided with a filling thimble 27, which is adapted to be normally sealed by a cap 28, which is suitably secured in position. It will be noted that the upper ends of the radiating and condenser tubes 25 and 26, respectively, are arranged adjacent the lower end 29 of the upper tank 23 at opposite sides of a suitably secured partition 30, the upper end of which extends to a point above the normal level of the liquid within the circulating system. It is also to be noted that a partitional wall 31 is arranged in the lower tank 24 between the lower ends of the radiating and condensing tubes 25 and 26 respectively.

A reservoir or tank 32, provided with a vent 33, arranged adjacent its upper end, and a port 34 formed in its lower end, is located below the outlet port 37 of the condenser, and may be suitably secured to the crank case 10 as by bolts 35. A conduit 36 is adapted to connect the port 37 in the condensing tank 38 of the radiator 13, with the port 34 of the tank 32.

Having described the general construction

and arrangement of the various parts, the operation of a preferred form of my cooling system will be understood as follows:—

As the temperature of the cooling medium rises above the vaporizing point of the cooling liquid, the vapor generated will be discharged into the upper end of the condensing tubes 26, and downwardly therethrough. On account of the fact that these tubes are arranged in the front of the fan 14, and the radiator tubes 25, all of the air which passes through these parts will first cool the condensing tubes 26 and then the radiator tubes 25, with the result that any vapor within the tubes 26 will be cooled and thereby condensed, then flowing into the lower tank 32, then through the port 37, conduit 36 and finally entering through the port 34 to the interior of the tank 32.

It will, of course, be understood that as the liquid within the circulating system, cools, after having discharged a considerable quantity therefrom through the condenser tubes 26 in the form of a vapor, a partial vacuum will be produced in the system with the result that the pressure of the atmosphere acting on the tank 32 through the vent 33, will automatically return the discharged liquid from the tank back through the conduit 36 and condenser tubes 26, to the upper part of the radiator 13.

It will, of course, be understood also that in the event the level of the liquid within the cooling system rises above the predetermined normal for any reason, the surplus will flow over into the condenser and be served in the tank 32. In actual practice, I prefer to retain a small quantity of liquid in the bottom of the tank 32 to serve as a condenser in the event that the cooling effect of the tubes 26 is not sufficient to reduce the vapor to a liquid state.

While I have described and will specifically claim what I deem to be a preferred form of my invention, it, of course, will be obvious to those skilled in the art that various modifications and changes may be made without departing from the spirit and scope hereof.

Having thus described my invention, what I claim and desire to secure by Letters Patent is:—

1. In an internal combustion engine, in combination, a cylinder jacket, a cooling device, and connections therebetween, and a condensing device arranged in line with said other device and connected with the upper part thereof, and means for circulating air about said devices whereby said condensing device is subjected to the cooling action of the air which passes over said other device.

2. In an internal combustion engine, in combination, a cylinder jacket, a radiator and connections therebetween, of a condenser and a fan arranged in line with said

radiator and condenser, said condenser having an inlet connecting with the upper part of said radiator.

3. In an internal combustion engine, in combination, a cylinder jacket, a radiator and connections therebetween, of a condenser and a fan arranged in line with said radiator and condenser, said condenser having an inlet connecting with the upper part of said radiator, and a tank connected with the lower part of said condenser.

4. In an internal combustion engine, in combination, a cylinder jacket, a radiator, and sealed connections therebetween, of a fan arranged at one side of said radiator, and a condenser arranged at the other side of said radiator and subject to the effects of said fan and having an inlet connected with the upper portion of said radiator, said condenser also having an outlet arranged adjacent its lower end.

5. In an internal combustion engine, a cylinder jacket having an inlet port and outlet port, a radiator having similar ports and connections therebetween for forming a sealed circulating circuit, a condenser comprising tubes mounted on said radiator and having an inlet port connected with the upper part of said circuit.

6. In an internal combustion engine, a cylinder jacket having an inlet port and an outlet port, a radiator having similar ports and connections therebetween for forming a sealed circulating circuit, a condenser comprising tubes mounted on said radiator and having an inlet port connected with the upper part of said circuit, and having an outlet port arranged adjacent the lower end thereof.

7. In an internal combustion engine, a cylinder jacket having an inlet port and outlet port, a radiator having similar ports and connections therebetween for forming a sealed circulating circuit, a condenser comprising tubes mounted on said radiator and having an inlet port connected with the upper part of said circuit, and having an outlet port arranged adjacent the lower end thereof, a tank arranged below said condenser outlet port a connection between said latter mentioned outlet port and the lower portion of said tank, said tank having a vent adjacent its upper portion.

8. In an internal combustion engine, in combination, a cylinder jacket, a cooling device connected therewith and comprising a plurality of sets of tubes, one of which sets is adapted to cool the liquid circulating through said jacket and another of which set is in communication with said other set at a point about the normal level of liquid therein, whereby any vapor formed within said jacket will be discharged into said second set of tubes for condensing the same.

9. In an internal combustion engine, in

combination, a cylinder jacket, a cooling device connected therewith and comprising a plurality of sets of tubes, one of which sets is adapted to cool the liquid circulating through said jacket and another of which sets is in communication with said other set at a point about the normal level of liquid therein, whereby any vapor formed within said jacket will be discharged into said second set of tubes for condensing the same, and a fan arranged in line with said device.

10. In an internal combustion engine, in combination with a cylinder jacket, a perforate radiator and connections therebetween of a perforate condenser arranged in front of said radiator and connected with the upper portion thereof.

11. In an internal combustion engine, in combination with a cylinder jacket, a radiator, and connections therebetween, of a condenser arranged in front of said radiator and connected with the upper portion thereof, and a fan in line with said radiator whereby a current of air may pass through said radiator and condenser as and for the purpose specified.

12. In an internal combustion engine, in combination with a cylinder jacket, a radiator and connections therebetween of a condenser arranged in front of said radiator and connected with the upper portion thereof, and a fan in back of said radiator where-

by a current of air may pass through said radiator and condenser as and for the purpose specified.

13. In an internal combustion engine, a cylinder jacket, a radiator, and sealed connections therebetween of a condenser in line with said radiator and complementary thereto and having a connection with a point above the normal level of liquid therein, and a tank below the lowermost level of said liquid and connected with the lower part of said condenser.

14. In an internal combustion engine, a cylinder jacket, a radiator, and connections therebetween, of means for condensing any vapor formed in said radiator comprising a coil mounted in said radiator and in communication with the interior at a point about the normal level of liquid therein, and a vented tank connected with the lower portion of said condenser, the entire arrangement being such that the vapor formed within said radiator will be passed through said coil and condensed therein, the condensation being discharged from the lower end of said coil to said tank and returned from said tank through said coil to said radiator by the pressure of the atmosphere, as the liquid within the system cools.

In testimony whereof I affix my signature.

DWIGHT T. RANDALL.
